(57) **CLAIM**

The ornamental design for a portable sign, as shown and described.

DESCRIPTION

FIG. 1 is a front perspective view of a portable sign shown in a first usage environment of the present disclosure; FIG. 2 is a front perspective view of the portable sign as shown in FIG. 1;

FIG. 3 is a right side elevation view thereof;

FIG. 4 is a top perspective view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a front perspective view of the portable sign of FIG. 1 shown in an alternative position;

FIG. 10 is a front elevation view of the portable sign shown in FIG. 9;

FIG. 11 is a front perspective view of a portable sign illustrated in accordance with an alternate embodiment of the present disclosure;

FIG. 12 is a rear perspective view thereof;

FIG. 13 is a right side elevation view thereof;

FIG. 14 is a front elevation view thereof;

FIG. 15 is a rear elevation view thereof; and,

FIG. 16 is a top plan view thereof, the bottom plan view being identical to the top plan view thereof.

The evenly spaced dash-dash broken lines illustrate environment that forms no part of the claimed design. The dash-dot-dot broken lines illustrate a score line.
